UNITED STATES PATENT OFFICE.

PHILIP HAUSER, OF NEW YORK, N. Y.

CIGAR-BOX OPENER.

1,149,138.

Specification of Letters Patent.

Patented Aug. 3, 1915.

Application filed March 29, 1911. Serial No. 617,658.

To all whom it may concern:

Be it known that I, PHILIP HAUSER, a citizen of the United States, residing at New York, in the county of New York and State of New York, have invented new and useful Improvements in Cigar-Box Openers, of which the following is a specification.

My invention relates to box openers and particularly to that class of box openers wherein the same is inserted during the operation of packing and is retained in position until opening of the box is desired.

It is my object to provide a box opener of this type which will be a small, simply-constructed device adapted for insertion between the upper edge of the front wall of the box and that portion of the hinged cover impinging thereupon when in closed position, said device so positioned prior to the closing of the box and provided with an extension or projection disposed beyond the side of the box adapted to be grasped by the hand, turning which is designed to effect the expeditious and ready opening of the box.

Another object of my invention is to provide a box opener so constructed as to be impossible to dislodge or displace it once the box has been sealed except in the capacity for which designated.

A still further object of my invention is to provide a box opener which will be simple, light, durable and economical of manufacture.

With the foregoing and other objects in view my invention consists in such details of construction and in the arrangement and combination of parts as will be hereinafter more fully described and specifically pointed out in the appended claim.

In describing my invention in detail reference will be had to the accompanying drawings, in which like characters denote like or corresponding parts throughout the several views and in which—

Figure 1 is a perspective view of the device applied to a box disclosed in section and with the lid raised. Fig. 2 is a cross sectional view of the device applied to a box, the lid being closed. Fig. 3 is a similar view disclosing a modification of the device, and Fig. 4 is a perspective view of the modified form of the device.

Referring to the drawings the opener comprises preferably a single sheet of metal stamped and bent to provide a lifting plate 10 for engagement upon the upper edge

of the front wall 11 of a box and adapted to receive the under surface of the cover 12 of the box impinging thereupon when closed. Inner and outer flanges 13 and 14 respectively extend in opposite directions from and at right angles to the inner and outer edges of the lifting plate 10. The outer flange 14 which extends up from the lifting plate 10 and is flared at its upper end, rests against the outer edge of the cover 12 and carries an outstanding finger piece or key 15. The finger piece 15 is also in the nature of a flange extending the full length of the upper flared edge of the flange 14 and having any suitable shape to adapt it for grasping by the fore-finger and thumb of the hand. The inner flange 13 which extends down from the plate 10, rests snugly against the inner side of the front wall 11 of the box and holds the lifting plate 10 from slipping out beneath the cover 12.

Referring to Figs. 3 and 4, disclosing a slight modification of the device, the upstanding flange 14^a is provided along its upper edge with spaced overturned tongues 16 receiving therebetween the overturned tongues 17 disposed along the inner edge of the finger piece 15^a. A pintle 18 passes through the registering overturned portions 85 of the tongues 16 and 17 whereby the finger piece is hingedly supported upon the aforesaid upstanding flange. The advantage derived in so hinging the finger piece 15^a is that in packing the same may be 90 folded down close against the front wall 11 of the box so as to economize space and eliminate all possibility of accidental opening during shipment.

For purposes of decoration the finger 95 piece may be of any suitable design thus providing an ornament as well as an article of genuine utility.

In the use of the opener the same is positioned on the edge of the front wall 11 of the box having the flange 13 resting against the inner side of said wall as disclosed to advantage in Fig. 1 of the drawings. The cover 12 is now closed as shown in Fig. 2 whereupon the upstanding flange 14 receives 105 the outer edge of the cover 12 and holds the finger piece 15 flush with the upper edge of the cover. In cases where the modification is employed, the finger piece is then turned down against the outside of the front of the box where it remains out of the way until 110 it is desired to open the box. In opening

the box the operator grasps the finger piece 15 and twists the same to effect the raising of the lifting plate 10 upon one edge whereby the cover is forced up from engagement 5 with the front wall 11.

I desire it to be understood that slight changes in the construction and in the arrangement and combination of the several parts may be resorted to without departing 10 from the spirit of my invention, provided such changes fall within the scope of the appended claim.

Having thus fully described my invention what I claim as new and desire to secure by 15 Letters Patent is:—

A combination of a box including a body portion, and a cover hingedly connected

with said body portion and resting upon the upper edges of the walls of said body portion when in a closed position, with an 20 opener including a wall resting upon the upper edge of one wall of said body portion, an inner wall extending downwardly into the body portion of the box from the first mentioned wall of said opener, an outer 25 wall extending upwardly from the first mentioned wall of said opener and a finger piece extending from the outer wall of said opener.

PHILIP HAUSER.
